(57) CLAIM

The ornamental design for an outdoor bench as shown and described.

DESCRIPTION

FIG. 1 is a top perspective view of an outdoor bench; FIG. 2 is a bottom perspective view thereof; FIG. 3 is a front elevational view thereof; FIG. 4 is a rear elevational view thereof; FIG. 5 is a left-side elevational view thereof; FIG. 6 is a right-side elevational view thereof; FIG. 7 is a top plan view thereof; and, FIG. 8 is a bottom plan view thereof.

The broken lines are for the purpose of illustrating portions of the outdoor bench which form no part of the claimed design. The broken lines of uneven length (i.e., dashed-dot lines) are for the purpose of illustrating the boundaries of the claimed design.

1 Claim, 8 Drawing Sheets
